US0D1043754S

(12) **United States Design Patent** (10) Patent No.: **US D1,043,754 S**
(45) Date of Patent: ** Sep. 24, 2024

(54) **OUTBOARD MOTOR TILLER**(71) Applicant: **Brunswick Corporation**, Mettawa, IL (US)(72) Inventors: **Robert A. Podell**, Slinger, WI (US); **Ryan C. Abellera**, Fond du Lac, WI (US); **Todd D. Dannenberg**, Fond du Lac, WI (US)(73) Assignee: **Brunswick Corporation**, Mettawa, IL (US)(**) Term: **15 Years**(21) Appl. No.: **29/717,576**(22) Filed: **Dec. 18, 2019**(51) LOC (14) Cl. **15-01**

(52) U.S. Cl.

(57) **CLAIM**

The ornamental design for an outboard motor tiller, as shown and described.

DESCRIPTION

FIG. 1 is a front perspective view of an outboard motor tiller according to our new and ornamental design; and,

FIG. 2 is a top plan view thereof.

The broken lines depict portions of the outboard motor tiller that form no part of the claimed design.
